UNITED STATES PATENT OFFICE.

ELISHA A. POST AND EMIL F. SCHMITZ, OF ALLEGAN, MICHIGAN.

BURIAL-CASKET.

1,348,579.

Specification of Letters Patent.

Patented Aug. 3, 1920.

Application filed May 17, 1919. Serial No. 297,737.

To all whom it may concern:

Be it known that we, ELISHA A. Post and EMIL F. SCHMITZ, citizens of the United States of America, and residents of Allegan, 5 county of Allegan, State of Michigan, have invented certain new and useful Improvements in Burial-Caskets, of which the following is a full and clear specification:

The object of this invention is to provide 10 a burial casket which shall be materially less expensive to build than the ordinary wooden casket and which at the same time will have greater strength in proportion to the thickness of the walls. In view of the increasing 15 scarcity of lumber suitable for casket-making, we have designed our casket to enable it to be constructed with a minimum of wooden parts, as more fully hereinafter set forth.

In the drawing—

20 Figure 1 is a vertical transverse section of our improved casket;

Fig. 2 is a detail vertical section through one of the lower moldings;

Fig. 3 is a side elevation partly in vertical 25 section;

Fig. 4 is a transverse section on the line 4—4 of Fig. 3; Fig. 5 is a horizontal section on the line 5—5 of Fig. 4.

The bottom wall A of our casket is constructed of a single panel consisting entirely 30 of a body of hardened plastic or cementitious material *a* inclosed in paper-board sheets *b* which adhere to the plastic mass and form virtually an integral part thereof. The edges 35 of this bottom panel are fastened to the bottom molding strips B by means of nails *c* driven through the edges of the panel and up into the molding. The molding is rabbed to the depth of the panel along its 40 lower inner corners, so that the bottom-face of the panel is flush with the bottom-edge of the molding. In this way, the rough edges of the plastic mass *a* and paper-boards *b* are virtually inclosed in the wooden body 45 of the molding, these edges abutting against the vertical wall *d* of the rabbet and thereby protecting the edges of the plastic filling as well as the paper-boards. In this way, a strong, durable and light bottom structure 50 is provided with the least possible use of lumber.

The upper inner edge of the bottom molding is rabbed in a manner similar to the bottom edge thereof to receive the lower 55 edges of the side-panels C, which panels are

made of the same materials and in the same manner as the bottom wall, the raw edges of the plastic body as well as the raw edges of the paper-boards *b* abutting against the upwardly-facing wall of the rack. In the top 60 edges of the panels C are nailed in the same manner the top moldings D, the lower edges of these top moldings being rabbeted to receive and protect the upper edges of the panels. In this way, a very substantial, 65 durable, light body structure is provided, the composite panels C being entirely sufficient in strength to withstand the usual strains. By rabbeting the moldings B and D along their inner corners, these moldings may 70 receive the usual ornamental finish on the exterior sides, leaving exposed only those portions of the panels which are smooth and finished. It will be observed also that, the outer surfaces of the panels being paper-board, they form a good adhering surface 75 for the glue used for fastening the finishing cloth thereon in those cases where finishing cloth is used; and in those cases where finishing cloth is not used, these paper-board 80 surfaces may be readily painted and varnished so as to be indistinguishable from wood.

The top section of the casket is made in the same manner as the body, the composite 85 side-panels E of the top section being rabbed into the inner corners of the molding strips F, while the top-panel G is similarly rabbed into the upper corners of the top molding strip H.

To reinforce the casket, we extend across the bottom at intervals a series of wood strips or battens *d* and nail or otherwise fasten the ends thereof to the base-moldings *b*; rabbing the ends of these base-strips 95 into notches in the moldings. The bottom panel is not only nailed to the corner moldings as set forth, but also nailed or otherwise fastened to these bottom battens. At two or more places along the length of the 100 casket, we fasten pairs of vertical strips *e* which form anchorages for the handles. These strips *e* are fastened at the lower ends to the base-moldings and at the upper ends to the margin or top moldings *d*. These 105 vertical strips *e* serve not only as anchorages for the handles, but also as braces for the side-walls, serving to tie the top frame *d* to the bottom frame *b* in a rigid manner and thus take the strain off the side panels, 110

this being particularly advantageous where, as in the present case, no vertical corner pieces or posts are used.

The nature and scope of the invention 5 having been thus indicated and its preferred embodiment having been specifically described, what is claimed as new is:

1. In a burial casket, bottom corner wooden moldings each rabbeted along its 10 lower inner corner to provide a vertical inwardly-facing wall and also rabbeted along its upper inner corner to provide an upwardly-facing wall, a panel forming the bottom wall having its edges fitted into said 15 lower rabbets, this wall being made of a hardened body of plastic material and facings of paper-board, the raw edges of this plastic material and paper-board being abutted against said vertical wall of the 20 rabbet, and side-panels of the same material as the bottom wall having their lower edges fitted into the rabbets formed along the upper edges of said corner moldings.
2. In a burial casket, bottom and top 25 margin moldings, unitary composite plastic panels connecting these moldings, and pairs of vertical battens lying against the interior of the walls and having their ends connected with the top molding as well as 30 the bottom molding, handles, fastening means for said handles extending through the side walls and being anchored in the vertical battens, substantially as described.
3. In a burial casket, top and bottom 35 margin moldings rabbeted along their edges, independent panels formed of plastic material and faced with paper-board having their raw edges inclosed and protected by being fitted into the rabbets formed

along the edges of said moldings, as and 40 for the purpose set forth.

4. In a burial casket, top and bottom margin moldings rabbeted along their edges, panels formed of plastic material and faced with paper-board, the edges of 45 said panels being fitted into and inclosed in the rabbets formed along the edges of said moldings, and reinforcing battens arranged along the inner side of said walls, as and for the purpose set forth. 50

5. In a burial casket, the combination of top and bottom margin moldings rabbeted along their edges, unitary panels formed of plastic material having their edges fitted into the rabbets formed along the edges of 55 said moldings to inclose and protect the same, and reinforcing battens arranged transversely of the bottom panels and having their ends anchored in the bottom moldings, as and for the purpose set forth. 60

6. In a burial casket, top and bottom margin moldings rabbeted along their edges, side panels formed of plastic material having their edges inclosed and protected by being fitted into the rabbets formed along the edges of said moldings, vertically-arranged battens disposed along the side panels and fastened to the inner faces of said moldings, handles, and securing means for said handles extending through the side panels and anchored in the 70 said battens, as and for the purpose set forth. 70

In testimony whereof we hereunto affix our signatures this 10th day of May, 1919. 75

ELISHA A. POST.
EMIL F. SCHMITZ.
